UNITED STATES PATENT OFFICE.

GEORGE W. ROTHROCK, OF INDIANAPOLIS, INDIANA.

DRAWING LIQUIDS FROM CASKS.

SPECIFICATION forming part of Letters Patent No. 350,157, dated October 5, 1886.

Application filed July 31, 1886. Serial No. 209,616. (No model.)

To all whom it may concern:

Be it known that I, GEORGE W. ROTHROCK, a citizen of the United States, residing at Indianapolis, in the county of Marion and State 5 of Indiana, have invented a new and useful Improvement in Drawing Liquids from Casks, of which the following is a specification.

My invention relates to an improvement in means for drawing liquids from casks.

10 The object of my improvement is to provide a vented bung for casks, to be used in connection with a faucet for drawing liquids from the casks, the bung-vent and faucet being so connected that the opening and closing of the 15 faucet shall operate to automatically open and close the vent.

The accompanying drawings illustrate my invention.

Figure 1 is a side elevation of the entire device. Fig. 2 is a plan of the same. Fig. 3 is an enlarged elevation of the vented bung. Fig. 4 is a front elevation of a part of the mechanism connecting the faucet and vent. Fig. 5 is a vertical section of the bung, showing the vent open. Fig. 6 is a front elevation of a modified form of the lever for operating the vent. Fig. 7 is a side elevation of the same.

The bung consists of the central portion, *b*, tapered toward one end to fit the bung-hole of 30 the cask *K*, and carrying on the outer projecting portion a collar, *f'*, which is held in place by the nut *n* and spring *sp*. Collar *f'* is provided with a radially-projecting hook, *i*, and is arranged to turn on the part *b*, and has a 35 hole, *o*, which, when the collar is turned to the proper point, registers with a hole, *o'*, passing radially from the outside of the bung *b* to the hollow interior *o'* of the bung, which communicates with the interior of the cask.

40 F is a faucet of ordinary construction, except that the turn-valve *c'* is provided with a radially-projecting hook, *h*. A short standard, *u*, is secured to the faucet near the cask by a clamp, *c*, and set-screw *s'*. A lever, *l*, is

pivoted at *p* to the standard *u*. The opposite 45 ends of lever *l* are connected, respectively, with the hook *i* on collar *f'* and the hook *h* on the turn-valve *c'* by connecting-rods *r* and *r'*.

For the purpose of adjusting the combined length of rods *r* and *r'* to the distance between 50 the bung and the turn-valve of the faucet, rod *r'* is made in two parts, the overlapping ends of which are secured together by a clamp, *s*. The same result may be attained by the modification of lever *l* shown in Figs. 6 and 7. 55 Short links *a* and *a'* are secured to opposite ends of the lever by means of the thumb-clamps *n n*, and these links may be adjusted at different angles to the lever to form bent continuations thereof, as shown.

For the purpose of forming a stop for collar *f'* at the point when holes *o* and *o'* coincide, a pin, *st*, projects from the bung in the path of a pin projecting from collar *f'*, as shown in dotted lines, Fig. 1.

The operation of my device is as follows: When the faucet is closed, the parts are in the position shown in full lines in Figs. 1 and 2, and the vent is closed. When the faucet is opened by turning valve *c'*, collar *f'* is also 70 turned by means of the connecting-rods *r* and *r'* and lever *l*, which assumes the position shown in dotted lines, Figs. 1 and 2, thus bringing holes *o* and *o'* to coincide, and permitting the ingress of air while the liquid contents of the cask are being drawn out through the faucet.

I claim as my invention—

The combination, with the cask and the faucet having turn-valve *c'*, of the bung *b*, having 80 openings *o* and *o'*, collar *f'*, having opening *o*, standard *u*, clamp *c*, lever *l*, and connecting-rods *r* and *r'*, all arranged to co-operate as and for the purpose specified.

GEO. W. ROTHROCK.
